UNITED STATES PATENT OFFICE.

RICHARD SCHNEIDER, OF DRESDEN, GERMANY.

FURNACE FOR WORKING ZINC AND LEAD.

SPECIFICATION forming part of Letters Patent No. 605,802, dated June 14, 1898.

Application filed March 18, 1897. Serial No. 628,213. (No model.)

To all whom it may concern:

Be it known that I, RICHARD SCHNEIDER, civil engineer, a subject of the King of Saxony, residing at Dresden, in the Kingdom of Saxony, German Empire, have invented new and useful Improvements in Furnaces for Working Zinc and Lead, of which the following is a specification.

My invention relates to improvements in furnaces for working zinc off its ores, and especially such ores as contain a considerable quantity of lead; and its object is to produce the zinc and lead simultaneously without thereby injuring the retorts, so that in the furnaces which form the subject of this invention ores can be worked which for the destructive influences on the retorts of the lead they contain cannot be treated in the furnaces that are at present in use.

The improvements consist mainly in the particular arrangement of separate receivers illustrated in the accompanying drawings for collecting the vapors of zinc developed in the retort and of the lead which smelts from the ore.

The drawings represent, in Figure 1, a vertical section of the entire furnace, taken through line 1 1 in Fig. 2; Fig. 2, a horizontal section of the same, following the line 2 2 in Fig. 1; Fig. 3, a cross-section taken through line 3 3 in Fig. 1. Fig. 4 shows the upper receiving vessel or condenser adjoining the retort, drawn on a larger scale. Figs. 5 and 6 are sections through a retort, showing the position therein of the extremities of the upper and the lower receiver.

Similar letters refer to similar parts throughout the several views.

The general arrangement of the furnace does not differ essentially from that of the furnaces in use, as the retorts *a* are arranged in series in one or two chambers *b b* and subjected to a suitable heating, as required by the process. This heating may be effected, by way of example, by means of a regenerative gas-furnace, the gas and air regenerators being indicated in the drawings by the letters of reference *c* and *d*, and the gas-burner by the letter *c'*. This gas-furnace with generators being known to all those skilled in the art, no further explanation thereof is required.

As clearly shown by Figs. 2 and 3, the retorts *a* of the furnace, instead of being open only on one side, as usual, are open on both sides. From the upper side of each retort, which with preference is situated in an inclined position, there projects in a well-known manner the receiver *e* for the vapors of zinc developed in the retort, the receiver having the purpose of condensing said vapors and of collecting the metallic zinc. In combination with this receiver a tubular extension *g*, as customary, may be provided for in such a way as to be easily removed, if required. At the other and lower end of each retort another receiver *f* is arranged, tightly closed at its outer end, so as to prevent the atmospheric air from entering. This has the purpose to collect the metallic lead which smelts from the charge contained in the retort.

Both the receivers are provided with a trough *e'* and *f'* on their soles to facilitate the collection of the metallic zinc on one side of the furnace and of the metallic lead on the other side. The vapors of zinc rising from the ore treated in the retorts will pass over into the upper receiver *e* and condense there, with the effect of forming metallic zinc, while the lead separated at the same time from the ore in consequence of its greater specific gravity will flow downward, enter the lower receiver *f*, and collect in the trough *f'*. The process being finished, the metallic zinc may be taken from the upper receiver and the metallic lead from the lower receiver.

The merits of an arrangement substantially as here specified consist in the possibility not only of working zinc and lead out of its ores simultaneously, but also of collecting the liquid lead not in the hot retort, but in a cooler receiver, which has only a temperature sufficient to keep the lead in molten state, so as to permit the single drops of lead to flow down into the trough. The lead being drawn from the retorts immediately after its separation from the heated ore cannot, as in the furnaces which are at present in use, destroy the walls of the retorts, such destruction being generally the cause of great losses in zinc and in lead.

What I claim as my invention, and desire to secure by Letters Patent, is—

1. The combination in a furnace for work-

ing zinc, of the retorts for containing the ore to be treated, each provided with an upper receiver *e* for the zinc-vapors to be condensed therein arranged on one end of the retort and 5 a lower receiver *f* on the opposite end for the lead which smelts from the ore, and with means for collecting the zinc and the lead separated from one another; substantially as described.

10 2. In a furnace for working zinc; the combination with the retorts *a* of an upper receiver *e* for the zinc-vapors and a lower re-

ceiver *f* for the liquid lead, and of troughs *e'*, *f'* on the soles of said receivers for simultaneously collecting one the metallic zinc and 15 the other the metallic lead; substantially as and for the purpose set forth.

In testimony whereof I have hereunto set my hand in the presence of two subscribing witnesses.

RICHARD SCHNEIDER.
